Design No. 445.—

Design for Stoves

Patented Feb. 10, 1852.

Des. 445

Conrad Haas & Paul Wm. Zinner of Cincinnati, Ohio;
Letters Patent No. 445. Dated Feb 10th 1852

The Schedule referred to in these Letters Patent, and making part of the same

To all whom it may concern.

Be it known that we Conrad Haas and Paul Wm. Zinner, both of Cincinnati, Hamilton County, State of Ohio, have invented a new and useful design for Coal and Wood Parlor
Stoves, and we do hereby declare the following to be a full and exact description of the same, to wit, A showing a perspective view of the stove. What we claim as our invention, is the combination of the scrolls & foliage, arranged as set forth in the annexed drawings, so as to form an ornamental design for Coal & Wood Parlor Stoves, to be known and called the Sans Parlor.
